UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

OIL-WELL PACKER.

1,009,327.

Specification of Letters Patent. Patented Nov. 21, 1911.

Application filed June 21, 1911. Serial No. 634,557.

To all whom it may concern:

Be it known that I, PATRICK H. MACK, a citizen of the United States, residing at Bradford, in the county of McKean and 5 State of Pennsylvania, have invented certain new and useful Improvements in Oil-Well Packers; and I do hereby declare the following to be a full, clear, and exact description of the invention, such as will enable others skilled in the art to which it 10 appertains to make and use the same.

My invention relates to that class of devices termed oil well packers, used in conjunction with casing or tubing in oil or 15 Artesian wells for the purpose of shutting off water of the higher levels from a lower portion of the well or from the oil bearing sands.

More particularly my invention relates to 20 that class of packers wherein slips and a conical sleeve to expand the slips are employed to support the packer at the desired point in the well under the superimposed load of the casing or tubing which com- 25 presses and expands the packer. In this class of packers as heretofore constructed difficulty has frequently been experienced in withdrawing the packer or changing its position in the well by reason of the slips en- 30 gaging obstructions in the well which caused the buckling or folding down of one or more of said slips to the permanent impairment of the packing devices as well as loss of time and labor in the removal of the packing 35 from the well. This trouble is due to the failure of the slips, as at present constructed, to properly contract or collapse when the conical sleeve is withdrawn from between the same. A further difficulty experienced 40 in that class of packers wherein a hook on the slip ring and a pin on the tubing or cas- ing are relied on to hold the slips in an operative position when introducing the packer into the well, has resulted from the 45 closure of the hook by its engagement with the pin when the slips are in their operative position and the hook is above and resting upon the pin; such closure of the hook prevent- 50 ing its subsequently taking under the pin to retract the slips when the packing is to be released and withdrawn from the well, or its position therein changed.

To overcome or obviate these two disadvantages of the present construction of this 55 class of oil well packers is the object of

my present invention. To this end I loosely connect the slips with the slip-cage and provide means independent of the slips for causing the collapse of the slips when the expanding device is withdrawn from between the slips, and such a construction embodies the main feature of my invention. 60

In order to prevent the closure of the hook by the pin when the slips are in operative position and the hook may be over 65 and resting on the pin, I provide the underside of the hook with inclined cam surfaces that meet at a point and which act on the pin to cause the rotation of the tube or casing and permit the escape of the pin 70 from beneath the hook, and such a construction embodies another feature of my invention.

There are other, minor, features of invention involving particular combinations and 75 elemental features of construction, ancillary to the main features of invention, all of which will hereinafter more fully appear.

In the drawings chosen for the purpose of illustrating my invention, the scope 80 whereof is pointed out in the claims, Figure 1 is a view in elevation, of an oil well packer embodying my invention, the parts being shown in the inoperative position as when being lowered into the well, Fig. 2 is a vertical central section of the packer, the parts occupying the same relative position as in Fig. 1, Fig. 3 is a vertical central section of the packer shown in Fig. 1, the parts being in their operative position or relation, that is to say, the slips and the packer expanded, Fig. 4 is a detached perspective view of one of the slips, Fig. 5 is a detached perspective view of the slip-cage, Fig. 6 is a horizontal sectional view taken in the 85 plane of the line 6—6 Fig. 1, and Fig. 7 is a horizontal sectional view of the cage and friction springs taken in the plane of the line 7—7, Fig. 1. 90

Like symbols refer to like parts wherever 100 they occur.

I will now proceed to describe my invention more fully so that others skilled in the art to which it appertains may apply the same. 105

In the drawings, A indicates the section of tubing or casing which carries the packer and a a collar or coupling thereon, as the case may be.

C indicates a compressible packer, pref- 110

erably a cylinder of rubber. The upper end of the cylindrical packer C abuts on the shoulder formed by the under surface of the collar or coupling a so that under certain 5 conditions the load of the superimposed tubing or casing rests upon the cylindrical packer C for the purpose of compressing and expanding the packer.

Directly below and having its upper end 10 in contact with the cylindrical packer C, is a conical sleeve D loose or movable on the tubing or casing A, the tapering portion d of said sleeve D extending downward between the slips, which slips when expanded 15 by said conical sleeve, engage the well walls or the inner wall of the casing, as the case may be, and anchor said conical sleeve so that the cylindrical packer C is compressed between said conical sleeve D and the collar 20 or coupling a and expanded to shut off any water above said packer.

1 indicates a cylindrical slip-cage, with which the slips 2 are loosely connected so as to have a tilting movement to and from the 25 conical sleeve D and the well walls or casing. The slip-cage 1 is preferably comprised of two rings 3 and 4 connected by the bars 5. The upper ring 3 is provided with a series of recesses or open slots 3^a for the reception of the reins 2^a of the loose or tilting slips 2 and with sunken seats 3^b for the reception of the free or movable ends of friction springs 6, the opposite ends of said springs being attached to the lower ring 4 30 of the cage. In order to cause the slips 2 to move up and down with the cage 1 as well as to permit them to tilt, the open slots or recesses 3^a are beveled on their inner faces as at 3^c and provided with shoulders as at 3^d which engage with corresponding bevels and shoulders on the reins 2^a of the movable slips 2.

The lower ring 4 of cage 1 is provided with a series of seats or recesses 4^a for the attachment of the lower or fixed ends of friction springs 6. The under side of cage ring 4 is provided with downwardly projecting inclined cam faces as at 4^b, 4^c which meet at a point and with a horizontal slot 4^d, constituting a hook for engagement with a pin 7 on the tubing or casing A. At the inner end of slot 4^d is a slight depression 4^e to receive and retain the pin 7. When the pin 7 is in slot 4^d the cage 1 and slips 2 are held down, or in the inoperative position as shown in Fig. 1, and this is the relative position of the parts at the time the packer is introduced into the well or when its position in the well is being changed. By rotation of 55 the tube or casing A the pin 7 can be caused to move out of slot 4^d and release the cage 1.

2 indicates the slips which are tiltingly connected with the cage by means of the slip reins 2^a. The slip reins 2^a are beveled on 60 their outer faces as at 2^b to correspond with

the bevels 3^c of the cage, and are provided with shoulders 2^c which take under the shoulders 3^d of cage ring 3 so that while the slips are loosely connected with the cage the slips are made to move up and down with the cage. The reins 2^a of the slips are also grooved longitudinally as at 2^d to form seats in which the free ends of the friction springs slide, and the connecting bars 5 between the rings 3 and 4 are grooved as at 5^a to form seats for springs 6. These several spring seats 3^b, 2^d and 5^a permit the friction springs 6 to close to the diameter of the cage and slips where the diameter of the well requires it, and furthermore they prevent the friction springs 6 from being forced off of the slips when the packer or casing is turned.

6 indicates the friction springs which are preferably of semi-elliptical or bowed form with one end secured to the lower ring 4 of cage 1. The principal function of these springs is to frictionally engage the walls of the well, or inner walls of a casing, and temporarily support the cage in the well or casing until the conical sleeve expands the slips. Their number will bear some relation to the size and weight of the packer. Certain of these springs, however, have in the present construction an additional function, namely, they bear upon the slips 2 above their movable connection with the cage so that at all times when the slips 2 are not expanded by the conical sleeve D said springs will impart to the slips an inward movement which will insure the collapse of the slips and prevent them from engaging with or being injured by any obstructions in the well when the packer is being withdrawn from the well or its position in the well changed. Under most conditions the friction springs 6 which engage the slips 2 will be sufficient to support the cage, but where more are desired the free ends of the auxiliary friction springs will be provided with the seats 3^b on the cage ring 1^a.

The slips 2 may be roughened on their outer faces, or serrated as indicated in Fig. 4 of the drawings.

The devices being constructed and combined substantially as herein pointed out, will operate as follows: The parts being in the relation shown in Fig. 1 of the drawings, that is to say, the slip cage 1 and slips 2 in their lowest position and the pin 7 in slot or hook 4^d, the packer is lowered to the required position in the well, or well casing, as the case may be, during which the friction springs 6 will be compressed and will frictionally engage the walls of the well or casing. The packer being in the desired position the casing or tubing A which carries the packer is rotated to move the pin 7 out of slot 4^d, the cage being meanwhile held

stationary in the well by friction springs 6. The slip cage 1 and slips 2 being thus released the descent of the tube A carrying with it packer C and conical sleeve D will 5 force the conical sleeve D between the slips 2 and press the slips into engagement with the walls of the well or casing which will effectively anchor the conical sleeve D, slips 2 and cage in the well. As the tube A is 10 movable through the packer C and the conical sleeve D and cage 1 are anchored in the well or casing the superimposed load of the tubing or casing acting through collar or coupling a will compress and expand the 15 rubber cylinder C or packer so as to effectually shut off all water above the packer.

When it is desired to change the position of the packer in the well or to withdraw the packer from the well, the tubing or casing 20 A is raised until the pin 7 is in line with slot 4^d of the cage, which movement of the tube or casing A permits the escape of the conical sleeve D from between the slips 2, the action of the free ends of the friction 25 springs 6 on the slips above their point of loose or hinged connection with the slip cage being such as to force the slips to tilt inward and out of the way of any possible obstruction in either well or casing. The 30 slips 2 being thus released, the tubing or casing A is rotated to carry pin 7 into slot 4^d of slip-cage 1, and the cage, packer, &c., can then be raised or lowered to any other desired position, or be withdrawn from the 35 well.

It will be noted that owing to the independently movable character of the slips and the friction springs and the nature of the combination or co-action of said members, 40 the slips must necessarily collapse sufficiently to avoid any possible obstruction in either well or casing; and it will be further noted that the cage and the pin 7 can never so engage that the hook or slot 4^d will be closed 45 and render the devices inoperative.

Having thus described my invention, what I claim and desire to secure by Letters Patent is:

1. In an oil well packer, the combination 50 of a slip-cage, slips having a loose connection with said cage, means for expanding the slips, and means acting on the slips

above their loose connection with the cage to cause the collapse of the slips when the expanding means is withdrawn. 55

2. In an oil well packer, the combination of a slip-ring, slips having a loose tilting connection with the slip-ring, means for expanding the slips, and springs acting on the slips above their loose or tilting connection 60 with the slip-ring for causing the collapse of the slips when the expanding means is withdrawn.

3. In an oil well packer, the combination of a slip-cage, slips loosely connected with 65 the slip-cage, means for expanding the slips, and friction springs secured to the cage and bearing on the slips above the loose connection of the slips with the slip cage.

4. In an oil well packer, the combination 70 of a slip-cage having shouldered recesses for the reception of slip reins, slips having reins provided with shoulders for loosely and tiltingly connecting with the slip-cage, friction springs secured to the slip cage, which 75 springs engage the slips at points above their tilting connection with the slip cage, and means for expanding the slips.

5. In an oil well packer, the combination of a slip cage having an open slot or hook 80 for the reception of a pin on the tubing to which the packer is attached, slips having a loose and tilting connection with the slip cage, friction springs secured to the slip cage, which springs engage the slips above 85 their loose and tilting connection with the slip-cage, and means for expanding the slips.

6. In an oil well packer, the combination of a slip-ring having cam inclines on its under surface which inclines meet at a point 90 and an open slot above said inclines for the reception of a pin, slips connected with said slip ring, means for expanding said slips, and a section of tubing on which said slip ring is movable, said tubing provided with 95 a pin for holding the slip-ring and slips out of engagement with the expanding means.

In testimony whereof I affix my signature, in the presence of two subscribing witnesses.

PATRICK H. MACK.
